UNITED STATES PATENT OFFICE.

THOMAS V. RANKIN, OF CINCINNATI, OHIO.

SAWING-MACHINE.

SPECIFICATION forming part of Letters Patent No. 474,189, dated May 3, 1892.

Application filed November 23, 1891. Serial No. 412,761. (No model.)

To all whom it may concern:

Be it known that I, THOMAS V. RANKIN, a citizen of the United States, residing at Cincinnati, in the county of Hamilton and State 5 of Ohio, have invented certain new and useful Improvements in Sawing-Machines, of which the following is a specification.

My invention relates more particularly to hand sawing-machines which are especially 10 designed and adapted to execute bevel and other cross-cut work, the construction and arrangement thereof being fully hereinafter described, and particularly pointed out in the claims.

15 In the accompanying drawings, Figure 1 is a longitudinal elevation of my invention, showing the parts in their normal condition or the position they assume for ordinary right angle or square cross-cut sawing, the auxiliary foot- 20 propelling strap being shown broken off at the fore end of the machine and the saw-carriage lying at or near the tail end of the bed-plate ready for a stroke or forward movement through the work; Fig. 2, a plan view of the 25 same; Fig. 3, a transverse sectional elevation in the direction of the arrow on line 1 1 in Figs. 1 and 2, but on a larger scale; Fig. 4, a broken vertical section on line 2 2 of Fig. 3; Fig. 5, a transverse sectional elevation in the di- 30 rection of the arrow on line x x in Figs. 1 and 2; Fig. 6, a transverse sectional elevation in the direction of the arrow on line y y in Figs. 1 and 2, excepting that the saw- 35 carriage bed-plate and accompanying recip- 40 roating devices are set at an angle of forty- five (45°) degrees, the position they assume when work of a corresponding angle or bevel is to be performed, a portion of the device be- 45 ing broken and in section to show the swivel 50 or central stud on which the sawing devices may be turned in a horizontal plane in setting them for bevel-work other than ordinary straight cross-cut or right-angled work; Fig. 55 1; Fig. 8, a broken longitudinal section on line 3 3 of Fig. 7; Fig. 9, a transverse sectional elevation in the direction of the arrow on line 4 4 of Fig. 7; and Fig. 10 a broken transverse 60 section, full size, simply showing the sliding 65 connection between the saw-carriage base- 70 plate and the longitudinal bed-plate of the 75 machine, the remaining parts being omitted.

A represents the longitudinal bed-plate of my machine provided along its upper face with the side guides or ways a a', which form 55 a straight track for the reciprocating movements of the saw-carriage, as most clearly shown in Figs. 2, 5, and 10. These side guides are each preferably formed in two parts, comprising the lower bars a² and upper bars 60 a³, which are of like width and jointly secured in place on the bed-plate by means of screws 65 a⁴. The lower bars a² are rabbeted along their upper inner edges to form the inner grooves a⁵ in said side guides. 65

B represents the base-plate of the saw-carriage, having one or more transverse plates or bars b secured to its under side, these bars b being shouldered or rabbeted at their opposite ends to correspond with and fit the 70 grooves a⁵ of the side guides, as clearly shown in Figs. 5 and 10. C represents a circular saw mounted perpendicular to said base-plate B on the outer end of the transverse shaft or arbor c, the latter being in turn 75 mounted in bearings on said base-plate B.

c' represents a small spur gear or pinion keyed to the inner end of saw-arbor c and driven by an engaging large spur-gear D, mounted on a short transverse shaft d, the 80 latter being in turn mounted in bearings on said base-plate B to the rear of said saw-arbor. d' is a bevel-pinion mounted on shaft d, adjacent said spur-gear D, and driven by an engaging bevel-gear E, which is mounted 85 at the tail end of a longitudinal screw-shaft F. The screw-shaft or spiral spindle F is journaled at its rear smooth end in bearings on said base-plate B, and its remaining spi- 90 ral portion engages the central opening of a ratchet-wheel e, the latter having a flanged hub e', which is journaled in a box at the top of standard or post E'. The standard E' is mounted upon the fore end of the bed-plate A and is supplied on its inner face with a 95 spring-controlled detent or pawl e², which en- 100 gages the ratchet-wheel e to prevent its turning backward, and also for the purpose I shall now describe. The central bore of the ratchet-wheel e is constructed with one or more spiral threads or ribs f, corresponding in pitch and number with the spiral grooves (two being shown in the drawings) in the longitudinal screw shaft or spindle F and de-

signed to cause the rotary movement of said spindle F, when the saw-carriage is advanced or moved forward over its track, the said detent e^2 preventing said backward movement 5 of said ratchet-wheel, thus simultaneously driving the train of gear and they in turn rotating the saw for cutting. In the reverse or backward movement of the saw-carriage the spiral-grooved spindle F does not revolve, 10 owing to the fact that the ratchet-wheel e is free to revolve forward, and thus the saw and its train of gears are at rest during said reverse movement.

F' represents the handle (of ordinary hand-saw handle or plane-stock form) attached at 15 the rear end of the saw-carriage for its propulsion in either direction.

An auxiliary foot device is preferably provided to aid the operator in executing work 20 on very hard lumber or expediting and facilitating work on any lumber. This foot device is composed of a belt or chain G, attached at one end to the loop or eye g in the fore end of the saw-carriage and leading over a roller or 25 idler g', journaling in an opening in the standard E' to a suitable foot-treadle, (not shown,) or, if desired, to any other motive power.

H represents a transverse bar or plate shouldered at its opposite ends to fit the inner 30 grooves a⁵ in the side guides and designed to serve as a stop gage or abutment on the bed-plate to limit the forward movement of the saw-carriage. This stop-gage is provided with an automatic spring-catch h, the lower 35 end of which engages either one of a longitudinal series of notches h' in the upper face of the bed-plate A, whereby it may be adjustably set or locked in place at any point on the bed between the saw-carriage and standard 40 E', and thus shorten or lengthen the stroke of said saw-carriage to suit the width of material to be cut. The outer end of the spring portion of the catch h is upturned or formed into a lip to facilitate the disengagement of its 45 pendent portion from the notches in the bed-plate when desired. When said catch has been raised or disengaged from the bed-plate, the stop-gage may be readily slid or moved in either direction in the side guides.

I represents a horizontal segment or arc of 50 half a circumference graduated in degrees from zero to ninety each way and properly numbered, its opposite ends being hinged in recesses formed in the bottom of the bed-plate 55 A, as shown in Figs. 1 and 8, so that said bed-plate and the hereinbefore described sawing devices supported thereby may hinge or be arranged at an inclination thereon.

I' is a radial bar or plate projecting inwardly from the segment I, midway between its ends, and also hinged at its inner end in a recess formed in the bottom of bed-plate A, midway between the ends of the latter.

J is a long lateral bar, upon which the segment I and its accompanying saw devices oscillate in a horizontal plane, the double-headed pin or bolt i forming the center of oscillation

and also the coupling or means of connection between the said radial bar I' of the segment and said bar J, as clearly shown in Fig. 6. Bar 70 J forms a squaring gage or abutment which is brought against one edge of the work for the sawing operation, the portion of the work to be cut away projecting beyond its inner rounded end j the distance required. 75

K is an index-block attached to the bar J at one side the center thereof and rabbeted or shouldered on its inner lower corner, so that it may project over the segment I, a thumb-screw L passing through said rabbeted 80 portion of the index-block for frictional engagement with said segment and thereby firmly clamping it in place at the desired angle. Segment I enables the arrangement of the bed-plate and sawing devices at any angle 85 in a horizontal plane to a scope of one hundred and eighty degrees, this being ninety degrees in either direction, the parts being readily and instantly adjusted to suit the desired angle and to saw either square, bevel, 90 or miter work.

M represents a graduated arc or quadrant of ninety degrees suitably numbered and projecting from the said radial bar I', being disposed inwardly (toward the sawing devices) 95 and passed through a slot in an arm m, which latter projects laterally from the bed-plate immediately over the said radial bar I'.

m' represents an index block or plate on the arm m, adjacent the arc M, and m² is a 100 thumb-screw passed through said index-block m' for frictional engagement with said arc, and thereby firmly clamping or sustaining the arm m in place at the angle it is desired to arrange the bed-plate and sawing devices. 105

The hinging of the bed-plate and its accompanying saw devices to the outer ends of the graduated segment I, and the provision of arc M in connection therewith, enable the machine to cut both square and bevel work, the 110 bevel-work being at angles perpendicular or transverse to the angles presented by said segment I.

In the operation of my device the saw-carriage may be readily reciprocated over its 115 straight track, and so geared as to rotate the saw at any desired speed, all the angling or beveling devices being very readily changed at any time to suit the degree or angle required, whereby soft and hard wood alike may be 120 sawed either square, cross-cut, or at any angle. The momentum the saw attains before reaching the work (which is about one-third the length of the bed) enables the work to be done with ease and a clean cut secured. 125

It is obvious that for ordinary square cross-cut sawing, which is straight across the grain, the segment I and arc M could be entirely dispensed with and omitted from the machine altogether and the balance of my machine operate just as well. It is also obvious that either of the arcs I and M could be dispensed with and the machine operate with but one of them, as desired, the changes re-

quired in either event being immaterial and unnecessary to describe or show herein.

I claim—

1. In a sawing-machine, the combination of a bed-plate having a suitable track thereon, a handled saw-carriage reciprocating on said track, a circular saw mounted on said carriage, a longitudinal spirally grooved or threaded shaft connected by a train of gearing with said saw, the outer end of which shaft engages a feather in a standard or post at the fore end of said bed-plate, and a suitable abutment bar or plate, which is rested against one edge of the work, substantially as and for the purpose herein set forth.

2. In a sawing-machine, the combination of the bed-plate having a suitable track or guideway thereon, a handled saw-carriage reciprocating on said track or guideway, a circular saw mounted on said carriage, a longitudinal driving spiral shaft connected by a train of gearing with said saw, the outer end of which shaft engages a feather in a standard or post at the fore end of said bed-plate, a lateral abutment bar or plate, which is rested against one edge of the work, and a horizontal graduated segment attached to said bed-plate and connected by a center bolt or swivel with said abutment-bar, substantially as and for the purpose herein set forth.

3. In a sawing-machine, the combination of the bed-plate having a suitable track or guideway thereon, a handled saw-carriage reciprocating on said track, a circular saw mounted on said carriage, a longitudinal driving spiral shaft connected by a train of gearing with said saw, the outer end of which shaft engages a feather in a standard at the fore end of said bed-plate, a lateral abutment bar or plate, which is rested against one edge of the work and to which the bed-plate is hinged, an upright graduated quadrant projecting from said abutment-bar, and a lateral arm or plate projecting from said bed-plate over said abutment-plate and which engages said quadrant, substantially as and for the purpose specified.

4. In a sawing-machine, the combination of the bed-plate having a suitable track or guideway thereon, a handled saw-carriage reciprocating on said track, a circular saw mounted

on said carriage and connected by a suitable train of gearing with a longitudinal driving spiral shaft, the outer end of which shaft engages a feather in a standard at the fore end of said bed-plate, a lateral abutment-bar which rests against one edge of the work, a horizontal graduated segment, to the opposite ends of which said bed-plate is hinged, and which segment is connected by a center bolt or swivel with said abutment-bar, an upright graduated quadrant projecting from said segment, a lateral arm projecting from said bed-plate over a central radial bar on the said segment, and suitable clamping devices for holding the saw-frame at the desired angle on both said segment and quadrant, substantially as and for the purpose specified.

5. In a sawing-machine, the combination of a bed-plate having a suitable track or guideway thereon, a handled saw-carriage reciprocating on said track, a circular saw mounted on said carriage, a spiral shaft connected by a train of gearing on said carriage with said saw, and a spiral feather in the upper end of a standard, which is mounted at the fore end of said bed-plate, said saw-carriage and its accompanying gears, saw, and spiral shaft on being propelled forward engaging said spiral feather, whereby said spiral shaft and gears are rotated, and they in turn driving the saw, substantially as herein set forth.

6. In a sawing-machine, the combination of a spiral or screw shaft suitably mounted at one end on a saw-carriage, a track or bed-plate for said carriage, a circular saw and intermediate mechanism between it and said spiral shaft, and a suitably-controlled ratchet-wheel mounted at the fore end of said bed-plate and internally threaded to correspond with and engage the spiral groove in said shaft, whereby said shaft is rotated on its forward stroke to in turn impart or communicate motion to the saw and at rest on the return or backward stroke, substantially as herein set forth.

In testimony of which invention I have hereunto set my hand.

THOMAS V. RANKIN.
